SUPPORTING DEVICE FOR RAILS

Filed Aug. 1, 1928

FIG. 1

FIG. 2

INVENTOR

JOHN J. MACKLEM

Munn & Co

ATTORNEYS

UNITED STATES PATENT OFFICE

JOHN J. MACKLEM, OF LOS ANGELES, CALIFORNIA

SUPPORTING DEVICE FOR RAILS

Application filed August 1, 1928. Serial No. 296,725.

- My invention relates to and has for a purpose the provision of a simple, substantial and inexpensive device by which a member such as a rail or beam can be firmly held and supported from another member, the device being adjustable in a manner to accommodate rails extending in different directions and angles relative to the supporting member.
- 10 It is another purpose of my invention to provide a supporting device of the above described character, particularly adapted, although not necessarily, for use with scaffolds of the general character embodied in my 15 U. S. Patent No. 1,593,945 issued July 27, 1926; and in this use of devices embodying my invention, the side rails or runners of the ladders of the scaffold are capable of being effectively held in a manner to firmly support 20 the ladders on the wheeled trucks or tables of the scaffold.

I will describe only one form of supporting device for rails embodying my invention, and will then point out the novel features thereof 25 in claims.

In the accompanying drawing,

Fig. 1 is a perspective view illustrating devices embodying my invention applied to a scaffold and supporting a ladder of the latter on a wheeled truck of the scaffold;

Fig. 2 is an enlarged fragmentary view in elevation, showing a pair of the devices embodying my invention, applied to the scaffold;

Fig. 3 is a sectional view taken on the line 3—3 of Fig. 2 and looking in the direction of the arrows; and

Fig. 4 is a sectional view taken on the line 4—4 of Fig. 3 and looking in the direction of the arrows.

Referring specifically to the drawing in which similar reference characters designate similar parts in each of the several views, my invention in its present embodiment 45 comprises a base member B of U form constructed of metal to provide a pair of spaced apart parallel portions in the form of arms 10 and 10^a and a connecting portion in the form of 50 a flat base 11 from the center of which projects

a threaded stud 12 provided with a wing nut 13.

The free ends of the arms 10 and 10^a are bifurcated to provide aligned recesses 14 and 14^a in which are journaled aligned trunnions 55 15 and 15^a projecting from opposite ends of the body 16 of a holding member H, to the end that the latter will be pivotally mounted on the base member B between the arms 10 and 10^a of the latter.

To confine the trunnions 15 and 15^a against displacement from their respective recesses, headed pins 17 extend transversely through the arms 10 and 10^a adjacent their free ends and bridge the open ends of the recesses, 65 the pins being threaded at one of their ends to receive nuts 18 for preventing displacement of the pins from the arms.

The body 16 of the holding member H is in the form of a cup to provide a socket 19 in 70 which an end of a rail or beam such as, for example, a side rail 20 of a ladder L of a scaffold is adapted to be received and confined, and to secure the rail 20 firmly in the socket 19 against endwise displacement therefrom a 75 threaded stud 21 is threaded into a side wall of the body 16 and is adapted to be screwed into engagement with the rail 20 so that the latter will be clamped in the socket 19 between the stud and the opposed side wall of 80 the body 16.

In the use of the device above described with a scaffold, a pair of the devices are employed for each ladder L, the base members B of the devices being secured upon a wheeled truck T of the scaffold by means of their threaded studs 12 which extend through slots 85 22 formed in the platform 23 of the truck, the wing nuts 13 securing the base members in fixed positions on the platform and the slots 22 in the latter permitting adjustment of the base members towards and away from each other to position the sockets 10 of the holding members H of the devices, in proper spaced relation to receive the lower ends of the side 90 rails 20 of the particular ladder to be supported. The base members are thus rendered 95 adjustable to accommodate ladders of different widths.

As the holding members H of the devices 100

are free to pivot on their respective base members, it will be clear that the devices automatically adjust themselves to the relatively inclined side rails 20 of the ladder L so that the rails will firmly seat in the sockets 19 and will be secured against displacement from the latter upon screwing of the studs 21 into engagement with the rails. The rails of the ladder will thus be firmly held and the ladder effectively supported from the truck T.

Furthermore, it will be manifest that in a broader aspect my invention contemplates the provision of a suitable base member capable of being secured to a support, and a holding member adjustably mounted on the base member in such manner as to be rendered capable of firmly holding a rail or beam extending in various directions or angles from the support.

Although I have herein shown and described only one form of supporting device for rails embodying my invention, it is to be understood that various changes and modifications may be made therein without departing from the spirit of the invention and the spirit and scope of the appended claims.

I claim:

1. A supporting device for rails comprising a base member having spaced apart portions provided with recesses, a holding member having means in which a rail is adapted to be received and confined, and trunnions on the holding member journaled in said recesses to pivotally mount the holding member on the base member.

2. A supporting device for rails comprising a base member having spaced apart portions provided with recesses, a holding member having means in which a rail is adapted to be received and confined, trunnions on the holding member journaled in said recesses to pivotally mount the holding member on the base member, and means for confining the trunnions against displacement from the recesses.

3. A supporting device for rails comprising a base member having spaced apart portions provided with recesses, a holding member having means in which a rail is adapted to be received and confined, trunnions on the holding member journaled in said recesses to pivotally mount the holding member on the base member, and means for confining the trunnions against displacement from the recesses comprising pins extending through said portions and bridging the recesses therein.

4. A supporting device for rails comprising a U shaped base member including spaced apart parallel portions bifurcated to provide alined recesses, a holding member having a socket in which a rail end is adapted to be received and confined, trunnions projecting from opposite ends of the holding member

and extending into said recesses to pivotally support the holding member on the base member between said portions of the latter, and means for confining the trunnions against displacement from the recesses.

5. A supporting device for rails comprising a U shaped base member including spaced apart parallel portions bifurcated to provide alined recesses, a holding member having a socket in which a rail end is adapted to be received and confined, trunnions projecting from opposite ends of the holding member and extending into said recesses to pivotally support the holding member on the base member between said portions of the latter, and means for confining the trunnions against displacement from the recesses comprising pins extending through said portions of the holding member and bridging the recesses thereof.

6. A supporting device for rails comprising a base member having a pair of spaced apart parallel arms and a connecting portion, the connecting portion having a threaded stud projecting therefrom and provided with a nut by which the base member is adapted to be secured to a support, said parallel arms being bifurcated to provide alined recesses, a holding member having a cup shaped body to provide a socket in which a rail end is adapted to be received and confined, trunnions projecting from opposite ends of the body and extending into said recesses to pivotally support the holding member on the base member, pins extending through said arms of the holding member and bridging the recesses of the arms to confine the trunnions against displacement from the recesses, and a set screw threaded into the holding member and adapted to engage the rail to secure the latter against displacement from the socket.

Signed at Los Angeles, in the county of Los Angeles, and State of California, this 29th day of June, A. D., 1928.
